Application November 26, 1932, Serial No. 644,476

10 Claims.

(CL 62—116)

This invention relates to refrigerating apparatus and more particularly to that type of apparatus which is adapted to furnish refrigeration for domestic purposes.

5 It is among the objects of this invention to provide a refrigerating apparatus in which a cabinet is coordinated in an improved manner with a mechanical refrigerating system so that the system may be easily removed from the cabinet.

10 It is a further object of this invention to mount a refrigerating system on a cabinet in an improved manner so that the system is efficient in operation and requires no exposed moving parts to produce efficient cooling currents of air.

15 Further objects and advantages of the present invention will be apparent from the following description, reference being had to the accompanying drawings, wherein a preferred form of the present invention is clearly shown.

20 In the drawings:

Fig. 1 is a vertical cross-sectional view of a refrigerating apparatus embodying features of this invention;

25 Fig. 2 is a top plan view of the apparatus shown in Fig. 1, with the cover removed; and

Fig. 3 is a view in perspective taken from the rear of the apparatus.

A refrigerating apparatus embodying features of this invention includes, in general, a cabinet 30 and a refrigerating system associated therewith.

The cabinet includes a food compartment 10 and an upper compartment 11 in which parts of the refrigerating system may be placed. The food compartment 10 is closed by one or more doors 11 and is cooled by the evaporator 12. The cabinet includes upstanding side walls 10a and a removable cover 10b.

35 The refrigerating system includes, in general, a compressor or refrigerant translating device 13, a condenser 14 and the evaporator 12. The compressor or device 13 forwards refrigerant under relatively high pressure through the line 15 to the upper part of the condenser 14 in which the refrigerant is liquefied and flows to the bottom header 16. From thence it flows, in liquid form, through the line 17 to a suitable expanding device or valve, not shown, associated with the evaporator 12 which then delivers the expanded refrigerant to the evaporator 12 where it evaporates and returns, in gaseous form, through the line 18 to the compressor or device 13.

40 The refrigerating system is associated with the cabinet in such a manner that it may be readily removed from the cabinet without the necessity of disconnecting the various parts of the refrigerating system from one another. To this end, the compressor or device 13 and the evaporator 12 are mounted on the removable wall 19. The condenser 14 preferably is of sheet metal construction, in which sheets 20 and 21 are welded together along the edges and along intermediate portions thereof, but are slightly spaced elsewhere to provide condensing passages in the main body of the condenser. The condenser is attached to the back of the cabinet by any suitable supporting means, and in this particular embodiment is shown as including reversed extensions 22 and 23 along the vertical edges of the condenser which extensions terminate in flanges 22a and 23a which are bolted to the back of the cabinet by means of bolts 24. Thus the entire refrigerating system may be removed from the cabinet by disconnecting the condenser 14 from the cabinet and removing the wall 19 upwardly after the cover 10b of the cabinet has been removed.

45 The condenser 14, because of its sheet-like construction induces upward convection currents of air which cool the condenser. The translating device 13 is enclosed in the compartment 11 in which preferably the top and three side walls do not permit the flow of air or are relatively resistant thereto. The rear wall of the compartment 11, however, is preferably provided with a relatively large opening 26. Means are provided which cause the upward convection currents flowing past the condenser 14 to create a cooling action on the compressor or refrigerant translating device 13. Preferably this is accomplished by providing a baffle 27, which is an extension of the condenser 14, this baffle passing through the opening 26 and being directed towards the compressor 13, and having centrally converging sides 28 and 29. The compressor, in this particular embodiment, includes a dome-like body 13a, which encloses the electric motor and compressing parts driven thereby, around which are placed an outwardly protruding baffle construction 13b which forms upwardly directed air passages 13c and 13d. The baffle 27 is provided with a semi-circular end 27a which partly surrounds the compressor 13 and is slightly spaced therefrom. The convection air current flowing upwardly between the condenser 14 and the rear wall of the cabinet, is partly or wholly directed by the baffle 27 into the lower part of the compartment 11 and then flows upwardly around the compressor 13, partly through the passages 13c and 13d, and out over the top of the baffle 27 and through the opening 26. By this action the compressor or refrigerant translating device 13 is subjected to the cooling

50 55

action of an air current, and dissipates the heat of compression and any other heat created in the device 12 to the passing air. Thus an efficient cooling action is insured for the condenser and compressor without exposure to view of unsightly mechanism.

While the form of embodiment of the invention as herein disclosed constitutes a preferred form, it is to be understood that other forms may be adapted, all coming within the scope of the claims which follow.

What is claimed is as follows:

1. A refrigerating apparatus comprising a cabinet having upstanding side walls, a refrigerating system associated with said cabinet, said system including a refrigerant translating device mounted on the upper part of said cabinet, a condenser and an evaporator, said condenser being mounted on one of said upstanding side walls and inducing a convection current of a portion only of the air from said condenser over said translating device.

2. A refrigerating apparatus comprising a cabinet having upstanding side walls, a refrigerating system associated with said cabinet, said system including a refrigerant translating device mounted on the upper part of said cabinet, a condenser and an evaporator, said condenser being mounted on one of said upstanding side walls, and means for causing the convectional flow of a portion only of the air induced over said condenser to produce a cooling action on said refrigerant translating device.

3. A refrigerating apparatus comprising a cabinet having upstanding side walls, a refrigerating system associated with said cabinet, said system including a refrigerant translating device mounted on the upper part of said cabinet, a condenser and an evaporator, said condenser being mounted on one of said upstanding side walls, and means for directing a convection current of a portion only of the air from said condenser to said refrigerant translating device.

4. A refrigerating apparatus comprising a cabinet having upstanding side walls forming a food compartment and an upper compartment above said food compartment, a refrigerating system associated with said cabinet and including a refrigerant translating device mounted in said upper compartment, a condenser mounted on one of said side walls, an evaporator in thermal exchange with said food compartment, and a baffle deflecting convectional flow of air from said condenser into said upper compartment and also forming an air outlet from said upper compartment.

5. A refrigerating apparatus comprising a cabinet having a door defining the front of said cabinet and having upstanding side walls forming a food compartment and an upper compartment above said food compartment, a refrigerating system associated with said cabinet and including a refrigerant translating device mounted in said upper compartment, a plate-like condenser mounted on the rear one of said side walls, an evaporator in thermal exchange with said food compartment, and a baffle having a portion arranged to deflect convectional air flow from said condenser into said upper compartment and out the rear of said upper compartment.

6. A refrigerating apparatus comprising a cabinet having upstanding side walls forming a food compartment and an upper compartment above

said food compartment, a refrigerating system associated with said cabinet and including a refrigerant translating device mounted in said upper compartment, a condenser mounted on one of said side walls, an evaporator in thermal exchange with said food compartment, and a baffle extending from above said condenser into said upper compartment below the top thereof for directing convectional current of air from said condenser through said upper compartment and out above said baffle.

7. A refrigerating apparatus comprising a cabinet having upstanding side walls forming a food compartment and an upper compartment above said food compartment, a refrigerating system associated with said cabinet and including a refrigerant translating device mounted in said upper compartment, a condenser mounted on one of said side walls, an evaporator in thermal exchange with said food compartment, said condenser having reversely bent vertical edges forming a flue between said condenser and one of said side walls of the cabinet and another flue between said condenser and a wall of the building adjacent to which said condenser may be placed, means for deflecting the flow of air from one of said flues into said upper compartment.

8. A refrigerating apparatus comprising a cabinet having upstanding side walls forming a food compartment and an upper compartment above said food compartment, a refrigerating system associated with said cabinet and including a refrigerant translating device mounted in said upper compartment, a condenser mounted on one of said side walls, an evaporator in thermal exchange with said food compartment, said condenser having reversely bent vertical edges forming a flue between said condenser and one of said side walls of the cabinet and another flue between said condenser and a wall of the building adjacent to which said condenser may be placed, and means for deflecting the flow of air from said first named flue into said upper compartment.

9. A refrigerating apparatus comprising a cabinet having upstanding side walls forming a food compartment and an upper compartment above said food compartment, a refrigerating system associated with said cabinet and including a refrigerant translating device mounted in said upper compartment, a condenser mounted on one of said side walls, an evaporator in thermal exchange with said food compartment, and means for deflecting part only of the air flowing over said condenser into said upper compartment.

10. A refrigerating apparatus comprising a cabinet having a door defining the front of said cabinet and having upstanding side walls forming a food compartment and an upper machine compartment above and aligned with said food compartment, a refrigerating system associated with said cabinet and including a refrigerant translating device mounted in said upper machine compartment, a plate-like condenser mounted on the rear one of said side walls, an evaporator in thermal exchange with said food compartment, said upper machine compartment having a horizontally disposed baffle extending into said compartment below the top thereof and positioned to deflect air into and out of the rear of said cabinet by convection currents of said condenser.
